UNITED STATES PATENT OFFICE.

LEE EDWARD MITCHELL, OF BOSTON, MASSACHUSETTS.

HYDRAULIC AIR-COMPRESSOR.

SPECIFICATION forming part of Letters Patent No. 637,144, dated November 14, 1899.

Application filed March 30, 1899. Serial No. 711,117. (No model.)

To all whom it may concern:

Be it known that I, LEE EDWARD MITCHELL, of Boston, in the county of Suffolk and State of Massachusetts, have invented a new and Improved Hydraulic Air-Compressor, of which the following is a full, clear, and exact description.

My invention relates to an improvement in devices for compressing air by the use of water and comprises novel features, which will be hereinafter described and claimed.

Reference is to be had to the accompanying drawings, forming a part of this specification, in which similar characters of reference indicate corresponding parts in all the figures.

Figures 1 and 2 are sectional elevations of my device, showing the parts in different positions, and Fig. 3 is a plan view of my device with the float and tank removed and with the central pipe and its surrounding sleeve in section.

The object of my invention is to provide a device which shall be operated by a flow of water to compress air and which shall also be simple in construction and not likely to get out of order and refuse to work. The mechanism of the device is included within a tank A, which acts as the cylinder within which the air is compressed. This cylinder is provided with a base C, to which the body of the tank is secured by means of flanges and bolts or by any other suitable means. This base is preferably provided with legs C³, which will raise it a short distance above the floor and provide room for the passage of the water-pipes. The tank is also provided with a dome A' of such size as to receive the float D⁸ and connected at its top with a pipe B, which contains a check-valve B' to prevent backflow of the air and to which pipe the air-delivery pipe is to be attached.

The base C is provided with a central aperture, and a tube D extends upwardly into the dome, through which tube the air is introduced to the tank. The upper end of said tube is coned or otherwise formed to constitute a valve-seat. Surrounding the upper end of the tube is a sleeve E, which is provided with side openings e for the passage of air and has its upper end covered by a cap E', between which cap and the end of the tube is held a washer e', of rubber or similar mate-

rial, which will form a valve. When the sleeve is down in the position shown in Fig. 1, the opening at the upper end of the tube is closed, while when the sleeve is raised to the position shown in Fig. 2 air is free to enter the tank.

Surrounding the tube D is a second sleeve D', which at its lower end supports a pan D². This sleeve is also provided with two collars d and d', located one near the middle of the tube and the other at its upper end. Between these two collars is placed the float D³, which is held in place by the collars, but is free to slide upon the sleeve within the limits of the collars.

Placed eccentrically of the center of the base are two openings, through which the water enters the tank and escapes therefrom. The water enters through a passage C², which is preferably formed within a boss extending downward from the base C, and escapes through a passage C', formed similarly in a downward extension of the base. The opening C', which communicates with the passage C², opens directly into the tank and is the outflow or discharge opening.

The passage C² communicates with a pipe H', which extends upwardly within the tank and is connected at its upper end with a horizontal passage or pipe H. Within the pipe H, at its upper end, is placed a check-valve h, which prevents backflow of water. Supported on the outer end of the horizontal pipe H is a pipe F, within which is placed a valve controlling the admission of water to the tank. This valve consists of the two disks G² and G³, which closely fit the pipe and are slightly separated from each other, both being mounted upon a valve stem or rod G. This rod projects from both ends of the pipe F and is supported in suitable bearings at each end thereof. The lower end of the pipe F is at some distance above the bottom of the tank and has free communication with the interior of the tank either by openings through the end of the pipe or openings f at the sides thereof.

Upon the lower end of the rod G is secured a valve G', by which the discharge-opening C' may be closed. Placed between the plate H⁴, which forms the base for the vertical pipe H', and the bottom of the tank is a sheet M of rubber or similar packing material, which

assures a tight joint where the water is admitted and forms a seat for the valve G'.

The pipe H' is provided with an upward extension, which, as herein shown, consists 5 of a plug H², screwed into the upper end of the pipe. This extension has a horizontal arm H³, within the end of which is formed a bearing receiving one end of a rock-shaft J. The other end of this rock-shaft is supported 10 in the upper end of a standard I. Mounted upon this rock-shaft is a sleeve K, from which projects an arm K², upon the outer end of which is a counterweight K'. This sleeve K also has two arms L, projecting oppositely, 15 one at each side of the sleeve D'. These arms are connected by means of links L' with the collar d upon the sleeve D'.

The shaft J has secured thereto two collars O², each of which is provided with an arm 20 having a lateral extension engaging one of the arms L. The arm O', which extends from one of the collars, passes beneath the arm L, while the arm O passes above the arm L. These two arms O and O' occupy different 25 angular positions, so that they will not be engaged by the arms L except at the ends of their swing. Secured to one end of the rock-shaft J is an arm J², which is connected with the upper end of the valve-rod G, so that when 30 the shaft J is rocked the valve consisting of the disks G² G³ will be raised or lowered.

The operation of my device is as follows: The valve G² G³ is supposed to be in its lowermost position, as shown in Fig. 1. The device is connected, through the passage C², 35 with a suitable source of water-supply. The water flowing through this passage passes the check-valve h and the valve G² G³, flowing upwardly through the pipe F and out into the tank. In this position of the valve G² G³ the 40 discharge-valve G' is closed. The tank will thus fill with water, which will rise above the pan D², filling the same. As the water rises and nears the upper end of the tank it of 45 course compresses the air with which the tank is filled and forces it by the check-valve B' as soon as the pressure becomes greater than that on the other side of the check-valve. As the water rises the float D³ is raised, engaging 50 the collar d' and carrying the sleeve D' with it until it engages and raises the valve-sleeve E. This lifts the valve e' and permits the air-pressure to blow off, thus relieving the water-discharge valve G' of some of its pressure, so that the counterweight K' is enabled 55 to lift this valve and at the same time close the water-inlet valve G² G³, thus cutting off the inflow of water and opening the discharge-valve. In order to balance the disk G³ and 60 cause it to move without having to overcome the pressure of the water, the second disk G² has been provided. By this means the pressure of the water acts in both directions equally and does not cause any resistance to 65 the motion of the valve. As the water is discharged through the opening C⁴ the float D³ will drop until it rests upon the collar d. The

weight of this float is, however, not sufficient to overcome the counterweight K' when in its lowermost position. As the water continues 70 to fall it finally uncovers the pan D², which is filled with water and is water-tight, so that the water cannot escape. This brings into effect an added weight, which is finally sufficient to overcome the resistance of the counterweight and to cause the sleeve D' to drop. When this is done, the counterweight is thrown upward and the valve-rod, with its attached valves, downward, thus closing the discharge-opening and opening the inflow- 80 opening.

The device is thus entirely automatic in its action and will continue as long as the water is supplied.

Having thus fully described my invention, 85 I claim as new and desire to secure by Letters Patent—

1. A hydraulic air-compressor, comprising a tank having an air-discharge valve, an air-inlet pipe extending upward within the tank 90 and terminating in a valve-seat, a valve adapted to rest upon said seat and guided in vertical movement by said pipe, a sleeve surrounding said pipe and carrying at its upper end a float and at its lower end a water-pan, water 95 inlet and discharge valves for the tank, connections for securing opposite action of said valves, a rock-shaft having a counterbalance-weight, and connections from the rock-shaft to the water-controlling valves and the sleeve 100 surrounding the air-inlet pipe, substantially as described.

2. A hydraulic air-compressor, comprising a tank having air discharge and inlet valves and a water-discharge opening in its bottom, 105 a cylinder within the tank in line with said water-discharge opening and connected with a water-supply, a rod extending through said cylinder, and having a water-inlet valve and a water-exit valve thereon, a float connected 110 with the air-inlet valve to control it, and a counterbalanced rock-shaft connected with the rod carrying the water-controlling valves and the air-inlet valve, substantially as described. 115

3. A hydraulic air-compressor, comprising a tank having air inlet and discharge valves and water inlet and discharge valves, a rod connected with both water inlet and outlet 120 valves to operate them, a rock-shaft having an arm connected with said rod, a sleeve journaled upon the rock-shaft and having a counterweight and lever-arms connected therewith, bent arms carried by the sleeve and extending on opposite sides of the arm upon the 125 rock-shaft, said bent arms being separated so as to engage the rock-shaft arms at the extremities of their swing, and a float connected with the lever-arms and adapted to overcome the counterweight, substantially as described. 130
